UNITED STATES PATENT OFFICE.

NICHOLAS H. SURDENIK, OF CHICAGO, ILLINOIS.

DRAFT-GEAR FOR CARS.

No. 914,990.

Specification of Letters Patent.

Patented March 9, 1909.

Application filed October 15, 1908. Serial No. 457,922.

To all whom it may concern:

Be it known that I, NICHOLAS H. SURDENIK, a citizen of Hungary, residing at Chicago, in the county of Cook and State of Illinois, have invented certain new and useful Improvements in Draft-Gears for Cars; and I do hereby declare the following to be a full, clear, and exact description of the invention, such as will enable others skilled in the art to 10 which it appertains to make and use the same.

The invention relates to draft gears for railway cars.

The primary object of the invention is the provision of a draft gear adapted more especially for cars, and comprises means for yieldably supporting the coupler and maintaining the same in a predetermined plane below the sills of the car truck, and the construction 20 thereof being strong, durable and easy of access for repair when necessary, and whereby the necessary spring buffering and drawing effect is imparted to the draw bar, and the movement of the draw bar against the resistance of its springs may be reduced or minimized consistent to the proper working thereof.

Another object of the invention is the provision of a draw gear for cars which can be 30 readily and quickly attached or detached from the car truck and that will effect a proper buffering and drawing resistance to the draft bar, the construction being thoroughly durable and inexpensive in the manufacture.

In the drawings accompanying and forming part of this specification is illustrated one form of embodiment of the invention which to enable those skilled in the art to practice the invention, will be set forth at length in 40 the following description while the novelty of the invention will be included in the claim succeeding said description, although it is to be understood that minor changes, variations and modifications may be resorted 45 to such as come properly within the scope of the claim succeeding the description without departing from the spirit of the invention.

In the drawings: Figure 1 is a side view in elevation of the coupler and spring mechanism of a draw gear. Fig. 2 is a top plan view. Fig. 3 is a longitudinal sectional view. Fig. 4 is a bottom plan view. Fig. 5 is a side elevation of the draw bar detached from the draw gear mechanism. Fig. 6 is a transverse sectional view on the line 6—6 of Fig. 1. 55

Similar reference characters indicate corre-

sponding parts throughout the several views in the drawings.

In the drawings the numeral 8 designates the end sill of a car frame or truck and 9 the center sills or stringers which latter are mounted upon a body bolster 10. Connected to the inner faces of the center sills are draft plates 11 the same supporting against their outer faces channel bars 12 which are 65 united by bolt fasteners 13. Mounted upon said channel bars are castings 14 the same formed with outwardly projecting annular bearing heads 15 each having a central opening in which is slidably mounted a guide pin 16 70 carrying a follower block 17 and surrounding the guide pin 16 is a coiled expansion spring 18 the latter having one end bearing against the bearing head 15 while the opposite end has its bearing against the follower block 17 75 and which follower block normally rests in a stop pocket 19 formed on the said casting. The said follower blocks 17 have formed thereon spaced ears or extensions 20 to receive therebetween a bar or key 21 the latter also 80 engaging correspondingly shaped openings 22 formed in the stop pockets 19 to accommodate the said bar or key. The bar or key 21 has mounted in opposite ends thereof cotter pins 23 to prevent lateral displacement 85 thereof when mounted in the openings 22 and between the extensions 20 of the follower blocks.

Movable longitudinally between the draft plates 11 is a draft or draw bar 24 the latter 90 having at its inner end a yoke 25 in which is supported a bearing block 26 supporting centrally thereof a tail bolt 27 to one end of which is connected a follower block 28 between which latter and the bearing block 26 95 is disposed a coiled expansion spring 29 the same having one end bearing against the follower block 28 while the opposite end has its bearing against the bearing block 26. In advance or in front of the follower block and 100 supported by the yoke 25 is a filling block or stop block 30, the latter containing a central slot 31 in register or coincident with a slot 32 formed in the front face of the follower block and through which slots pass the bar or key 105 21 to connect and position the draw or draft bar 24 between the draw plates supporting the channel bars 12 upon the car frame or truck.

Pressure of the draw bar in the backward 110 direction causes it to move the bar or key 21 which latter moves the follower blocks 17

against the tension of the coiled expansion springs 18, while under draft the bar or key 21 is held rigid and the draw bar slides over the follower block 28 compressing spring 29, thus 5 the said spring 29 operates against the forward pull of the draw bar and the springs 18 act against the rear movement of said draw bar and permits the same to have the limited movement desired.

10 Disposed within the springs mounted in the yoke 25 and castings 14 are supplemental cushioning springs 33 the same being of decreased size with respect to the springs 18 and 29 and having their bearing against the 15 follower and bearing blocks or heads.

What is claimed is—

In a draft gear, the combination of center sills, draft plates secured thereto, channel bars fixed to the outer face of said draft

plates, castings mounted upon said channel 20 bars, bearing heads formed on said castings, follower blocks slideable in said castings, cushioning springs interposed between the follower and bearing blocks, a draft bar slideably arranged between the draft plates, a 25 yoke carried by said draft bar, a bearing block mounted in said yoke, a follower block slideable in said yoke, a cushioning spring interposed between said bearing and follower blocks in the yoke and a key passing 30 through the follower blocks in the castings and yoke.

In testimony whereof, I affix my signature, in presence of two witnesses.

NICHOLAS H. SURDENIK.
